UNITED STATES PATENT OFFICE.

FRANCIS A. PETER, OF NEWSIDE, PENNSYLVANIA.

DESIGN FOR A FENCE.

No. 39,977.

Specification for Design.

Patented May 4, 1909.

Application filed February 5, 1909. Serial No. 476,330. Term of patent 7 years.

To all whom it may concern:

Be it known that I, FRANCIS A. PETER, a citizen of the United States, residing at Newside, in the county of Lehigh and State of Pennsylvania, have invented a new, original, and ornamental Design for Fences, of which the following is a specification, reference being had to the accompanying drawing, forming part thereof.

The drawing represents an elevation of the fence.

The design comprises ornamental posts A,

the ornamental panels B, each panel having ornamental sections C, and an ornamental gate resembling a fence panel and having an ornamental head or top piece D.

I claim:

The ornamental design for a fence substantially as shown and described.

FRANCIS A. PETER.
